UNITED STATES PATENT OFFICE

139,601

DESIGN FOR A SLIPPER

Bessie Casso, Boston, Mass., assignor to Matilda Silver, doing business as Sufix Manufacturing Co., Boston, Mass.

Application October 14, 1944, Serial No. 115,766

Term of patent 7 years

(Cl. D7—7)

To all whom it may concern:

Be it known that I, Bessie Casso, a citizen of the United States residing at Boston, in the county of Suffolk and State of Massachusetts, have invented a new, original, and ornamental Design for a Slipper, of which the following is a specification, reference being had to the accompanying drawing, forming part thereof.

In the drawing,

Fig. 1 is a perspective view of the left side of a slipper showing my new design;

Fig. 2 is a top view thereof; and

Fig. 3 is a perspective view of the right side of the slipper.

I claim:

The ornamental design for a slipper, substantially as shown.

BESSIE CASSO.
